(No Model.)

H. H. CROWELL.
DOUBLE POLE SNAP SWITCH.

No. 436,122.

Patented Sept. 9, 1890.

WITNESSES:

John Smith
Edw. V. Mack,

Howard H. Crowell INVENTOR

BY
Smith & Dennison
his ATTORNEYS

UNITED STATES PATENT OFFICE.

HOWARD H. CROWELL, OF SYRACUSE, NEW YORK.

DOUBLE-POLE SNAP-SWITCH.

SPECIFICATION forming part of Letters Patent No. 436,122, dated September 9, 1890.

Application filed May 22, 1890. Serial No. 352,792. (No model.)

To all whom it may concern:

Be it known that I, HOWARD H. CROWELL, of Syracuse, in the county of Onondaga, in the State of New York, have invented new and useful Improvements in Double-Pole Snap-Switches, of which the following, taken in connection with the accompanying drawings, is a full, clear, and exact description.

My invention relates to snap-switches for making and breaking double-pole incandescent circuits.

My object is to produce a double-pole switch cheap and durable in construction and of great utility.

My invention consists in the several novel features of construction and operation hereinafter described, and specifically set forth in the claims annexed.

It is constructed as follows, reference being had to the accompanying drawings, in which—

Figure 1 is a top plan view of the switch with the upper casing removed. Fig. 2 is a top view of the brushes secured to either end of a non-conducting cross bar or arm. Fig. 3 is a side view of the switch complete with the upper casing removed. Fig. 4 is a sectional elevation through the switch and cross-bar. Fig. 5 is a sectional detail of the lower end of the spindle. Fig. 6 is a top plan view of one side of the base and inclines, showing an insulated beading extending up between the contact-plates.

A is the base, of circular form, constructed substantially as shown and having a series of inclines 1 1 1 1, and preferably circularly, around the shank or spindle C. Upon the alternate faces of the inclines are secured contact-plates 2 and 3, insulated from each other by the beading 4, or they may be insulated simply by a space.

The contact-plate 2 has an arm extending over the side of the base and provided with an opening through which I insert the binding-posts 5, and about which the wire 6, conveying the current, is secured. The contact-plate 3 has an arm extending beneath plate 2, thence down the side of the base, and is secured by a binding-post, same as in Plate 2, and to this binding-post a wire is secured. The opposite incline is constructed similar to the one just described.

Through the center of the base I make an

opening of sufficient size to admit the sleeve 8, inclosing the lower end of the spindle C, passing down beneath the bottom. Around the lower end of the sleeve 8, I secure a coil-spring 9, and through the spindle and sleeve I insert a pin 10, which is adapted to play vertically and circularly in the recess 11, cut in the lower side of the base, as shown. The upper end of this sleeve 8 is provided with an outwardly-projecting flange fitting up against the lower side of the arm D, as shown in cross-section in Fig. 4. The said flange is rigidly secured to arm D either by inserting screws 65 through the flange into the arm or in any other well-known manner.

12 and 13 are the metallic brushes, constructed, as shown, with their free ends bifurcated and gradually bent down as they approach the end, with a slight upward turn at the extreme end or point. These brushes are secured to the cross-bar D, which is constructed of wood or other non-conducting material.

It will be observed that when the spindle C is turned from left to right by means of the thumb-piece E the brushes are caused to travel up the inclines, and when they pass the step or highest point the tension produced by the spring 9 forces them down, causing the snap, as required by the insurance regulations, and instantly either making or breaking the electric circuit, according to their position.

The alternate inclines not covered by the conducting-plates are simply constructed with the base of insulating material.

F is an exterior cover secured over the switch, having an opening in its center to allow the spindle to protrude far enough, and upon which is secured the thumb-piece.

What I claim, and desire to secure by Letters Patent, is—

1. A double-pole electric switch consisting of an insulated base provided with a series of inclines upon its upper side, all extending in the same direction, said inclines being alternately insulated and alternately provided with conducting-plates secured to the upper faces of said inclines, binding-posts having wires connected thereto and to the said conducting-plates, a vertical spindle having a sleeve inclosing its lower end and secured

loosely in the said base by a pin passing through the spindle and sleeve and extending beyond its edge, a recess for the end of said spindle to travel in, a coil-spring secured 5 about the lower end of said sleeve, and an insulated cross-bar secured to the upper end of the said sleeve and having bifurcated brushes secured to either end, substantially as described, for the purposes set forth.

10 2. A double-pole electric switch consisting of an insulated base provided with a series of inclines upon its upper side, all extending in the same direction, said inclines being alternately insulated and alternately provided 15 with conducting-plates, said conducting-plates each having an arm secured at its end by a binding-post, the arm of the inner plate extending some distance beneath the outer plate, an insulating-bead extending up between the conducting-plates, binding-posts 20

having electric wires connected thereto, a vertical spindle having a sleeve and closing its lower end and secured loosely in said base by a pin passing through the spindle and sleeve and extending beyond its edges, a recess for 25 said pin to travel in, a coil-spring secured about the lower end of said sleeve, and an insulated cross-bar secured to the upper end of said sleeve and having the spindle pass through it and provided with bifurcated 30 brushes secured to either end thereof, said brushes adapted to travel upon the incline, substantially as described, for the purposes set forth.

In witness whereof I have hereunto set my 35 hand this 19th day of May, 1890.

HOWARD H. CROWELL.

In presence of—

H. P. DENISON,
ELLA V. MACK.
